UNITED STATES PATENT OFFICE

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY

MINE CAR

Application filed June 8, 1925. Serial No. 35,737.

Reference is had to the accompanying drawings which illustrate the preferred form of the invention; though it is to be understood that the invention is not limited 5 to the exact details of construction shown and described, as it is obvious that various modifications thereof within the scope of the claims will occur to persons skilled in the art.

10 In said drawings:

Fig. 1 is a side elevation of a mine car constructed in accordance with this invention, parts being broken away to show other parts more clearly;

15 Fig. 2 is a top plan view of the mine car shown in Fig. 1;

Fig. 3 is a vertical transverse section taken on the line 3—3 of Fig. 2; and

20 Fig. 4 is a partial vertical transverse section of a mine car of modified construction.

This invention relates to mine cars and has as an object to provide an improved mine car of minimum height for a given capacity and which is of rugged and inexpensive construction and which will permit 25 of repairs or replacement of parts without excessive dismantling of the car. It is also an object of this invention to provide a mine car of the type described in which the center floor portion bracing means are secured to the upper surface of the center floor portion and in which the center floor portion may be removed for repairs or replacement without removing the journal boxes or axles 30 from the body of the car.

With these and other objects in view, a mine car constructed in accordance with this invention comprises, as shown in Figs. 1 to 3, angle sills 1 having deep vertical flanges 40 2 and narrow outwardly projecting horizontal flanges 3. The sills 1 are joined by plate 4 forming the center floor portion of the car and having upwardly extending flanges 5 along its side edges which contact 45 with the outer faces of the vertical flanges 2 of the sills 1 and are fastened to the sills by rivets 6. To the outwardly projecting flanges 3 of the sills 1 and in contact with the upper surfaces thereof rivets 7 secure plates 50 8 which extend outwardly horizontally from

the sills 1 to form the side floor portions of the car and are bent upwardly to form the car sides 9. The car sides 9 are provided with rolled-over portions forming reinforced upper edges 10.

The side floor portions of the plates 8 are provided with openings 11 to receive the upper portions of the car wheels 12, the openings 11 being covered by wheel hoods 13 secured to the plates 8 by rivets 14. The wheels 12 are mounted upon axles 15 which extend through openings in the vertical flanges 2 of the sills 1 and are mounted in journal boxes 16 having vertical flanges 17 secured to the vertical flanges 2 of the sills by bolts 18, the bottom bolts passing through notches in flanges 5 of the plate 4. The journal boxes 16 are formed with horizontal flanges 19 which support the horizontal flanges 3 of the sills 1 and the journal boxes 16 also directly support the side floor portions of the plate 8 and are provided with recesses to receive the heads of the rivets 14.

The sills 1 are connected by pressed axle 75 housings 20 of substantially an inverted U-shape which fit over the axles 15 and have laterally projecting flanges 21 which are fastened to the plate 4 by rivets 22. The axle 80 housings 20 decrease in width and increase in height towards the ends and at the ends are provided with outwardly projecting vertical flanges 23 fastened to the vertical flanges 2 of the sills 1 by rivets 24 and with horizontal outwardly projecting flanges 25 which overlap and are fastened to the plates 8 and outwardly projecting flanges 3 of the sills 1 by rivets 7, the heads of rivets 7 fitting into recesses in the journal box flanges 19.

At the center of the car there is provided a 90 brace 26 which is secured on top of the plate 4 by rivets 27 and extends through notches cut in the vertical flanges 2 of the sills 1 and the flanges 5 of the plate 4. The brace 26 is bent upwardly and outwardly to contact 95 with the outer portions of the lower surfaces of the side floor portions of the plates 8 and is bent upwardly to contact with the outer surfaces of the car sides 9. At the ends of the car and adjacent the axles 15, 100

there are provided, on both sides of the car, 60 portion comprising a plate having upwardly braces 28 which are similar to the brace 26 extending vertical flanges secured to the vertical flanges of said sills, outwardly projecting in that they are secured to the car sides 9, side floor portions of the plates 8 and plate 4 but which extend onto the plate 4 only far enough to provide a proper overlap for riveting.

The modified construction shown in Fig. 4 differs from the construction described above in having the sills 101 formed integral with the plates 108 forming the side floor portions and the car sides 109, the plates 108 being bent downwardly along lines parallel to one edge to form the vertical flanges of the sills 101 and upwardly along lines parallel thereto to form the car side floor portions secured to said side floor portions and sills.

10 In a mine car, sills having downwardly projecting vertical flanges, a center floor portion comprising a plate having upwardly projecting vertical flanges secured to the outer surfaces of said vertical flanges of said sills, 70 and reenforcing means extending from sill 80 along lines parallel to one edge to form the car side floor portions secured to said center floor portion.

15 It will be noted that in a car constructed in accordance with this invention, that the center floor portion or the journal boxes may be removed for repair or replacement without disturbing the connections of the remaining parts of the car and that in the construction shown in Figs. 1 to 3, the side floor portions may be removed without disturbing the journal boxes 16 or plate 4 to a small extent, by removing the journal boxes and passing between said reenforcing means and said center floor portion.

20 It will also be noted that the axle housings serve as compression members and prevent distortion of the car by the load on the center 75 journal boxes 16.

25 In a mine car, sills having outwardly projecting vertical flanges, a center floor portion comprising a plate having upwardly projecting vertical flanges secured to the outer surfaces of said vertical flanges of said sills, and reenforcing means extending from sill 80 along lines parallel to one edge to form the car side floor portions secured to said center floor portion.

30 In a mine car, sills having outwardly projecting vertical flanges, a center floor portion comprising a plate having upwardly projecting vertical flanges secured to the outer surfaces of said vertical flanges of said sills, and reenforcing means extending from sill 85 along lines parallel to one edge to form the car side floor portions secured to said center floor portion.

35 What is claimed is: 1. In a mine car, sills having outwardly projecting side floor portions secured to said 90 journal boxes 16, and axles mounted in said journal boxes 16 or plate 4, to a small extent, by removing the journal boxes and passing between said reenforcing means and said center floor portion.

40 It will also be noted that the axle housings serve as compression members and prevent distortion of the car by the load on the center journal boxes 16.

45 In a mine car, sills having outwardly projecting vertical flanges, a center floor portion comprising a plate having upwardly projecting vertical flanges secured to the outer surfaces of said vertical flanges of said sills, and reenforcing means extending from sill 95 along lines parallel to one edge to form the car side floor portions secured to said center floor portion.

50 In a mine car, sills having outwardly projecting vertical flanges, a center floor portion comprising a plate having upwardly projecting vertical flanges secured to the outer surfaces of said vertical flanges of said sills, and reenforcing means extending from sill 100 along lines parallel to one edge to form the car side floor portions secured to said center floor portion.

55 In a mine car, sills having outwardly projecting vertical flanges, a center floor portion comprising a plate having upwardly projecting vertical flanges secured to the outer surfaces of said vertical flanges of said sills, and reenforcing means extending from sill 105 along lines parallel to one edge to form the car side floor portions secured to said center floor portion.

60 In a mine car, sills having outwardly projecting vertical flanges, a center floor portion comprising a plate having upwardly projecting vertical flanges secured to the outer surfaces of said vertical flanges of said sills, and reenforcing means extending from sill 110 along lines parallel to one edge to form the car side floor portions secured to said center floor portion.

65 In a mine car, sills having outwardly projecting vertical flanges, a center floor portion comprising a plate having upwardly projecting vertical flanges secured to the outer surfaces of said vertical flanges of said sills, and reenforcing means extending from sill 115 along lines parallel to one edge to form the car side floor portions secured to said center floor portion.

70 In a mine car, sills having outwardly projecting vertical flanges, a center floor portion comprising a plate having upwardly projecting vertical flanges secured to the outer surfaces of said vertical flanges of said sills, and reenforcing means extending from sill 120 along lines parallel to one edge to form the car side floor portions secured to said center floor portion.

75 In a mine car, sills having outwardly projecting vertical flanges, a center floor portion comprising a plate having upwardly projecting vertical flanges secured to the outer surfaces of said vertical flanges of said sills, and reenforcing means extending from sill 125 along lines parallel to one edge to form the car side floor portions secured to said center floor portion.

80 In a mine car, sills having outwardly projecting vertical flanges, a center floor portion comprising a plate having upwardly projecting vertical flanges secured to the outer surfaces of said vertical flanges of said sills, and reenforcing means extending from sill 130 along lines parallel to one edge to form the car side floor portions secured to said center floor portion.

85 In a mine car, sills having outwardly projecting vertical flanges, a center floor portion comprising a plate having upwardly projecting vertical flanges secured to the outer surfaces of said vertical flanges of said sills, and reenforcing means extending from sill 135 along lines parallel to one edge to form the car side floor portions secured to said center floor portion.

90 In a mine car, sills having outwardly projecting vertical flanges, a center floor portion comprising a plate having upwardly projecting vertical flanges secured to the outer surfaces of said vertical flanges of said sills, and reenforcing means extending from sill 140 along lines parallel to one edge to form the car side floor portions secured to said center floor portion.

95 In a mine car, sills having outwardly projecting vertical flanges, a center floor portion comprising a plate having upwardly projecting vertical flanges secured to the outer surfaces of said vertical flanges of said sills, and reenforcing means extending from sill 145 along lines parallel to one edge to form the car side floor portions secured to said center floor portion.

100 In a mine car, sills having outwardly projecting vertical flanges, a center floor portion comprising a plate having upwardly projecting vertical flanges secured to the outer surfaces of said vertical flanges of said sills, and reenforcing means extending from sill 150 along lines parallel to one edge to form the car side floor portions secured to said center floor portion.

105 In a mine car, sills having outwardly projecting vertical flanges, a center floor portion comprising a plate having upwardly projecting vertical flanges secured to the outer surfaces of said vertical flanges of said sills, and reenforcing means extending from sill 155 along lines parallel to one edge to form the car side floor portions secured to said center floor portion.

110 In a mine car, sills having outwardly projecting vertical flanges, a center floor portion comprising a plate having upwardly projecting vertical flanges secured to the outer surfaces of said vertical flanges of said sills, and reenforcing means extending from sill 160 along lines parallel to one edge to form the car side floor portions secured to said center floor portion.

115 In a mine car, sills having outwardly projecting vertical flanges, a center floor portion comprising a plate having upwardly projecting vertical flanges secured to the outer surfaces of said vertical flanges of said sills, and reenforcing means extending from sill 165 along lines parallel to one edge to form the car side floor portions secured to said center floor portion.

120 In a mine car, sills having outwardly projecting vertical flanges, a center floor portion comprising a plate having upwardly projecting vertical flanges secured to the outer surfaces of said vertical flanges of said sills, and reenforcing means extending from sill 170 along lines parallel to one edge to form the car side floor portions secured to said center floor portion.

125 In a mine car, sills having outwardly projecting vertical flanges, a center floor portion comprising a plate having upwardly projecting vertical flanges secured to the outer surfaces of said vertical flanges of said sills, and reenforcing means extending from sill 175 along lines parallel to one edge to form the car side floor portions secured to said center floor portion.

130 In a mine car, sills having outwardly projecting vertical flanges, a center floor portion comprising a plate having upwardly projecting vertical flanges secured to the outer surfaces of said vertical flanges of said sills, and reenforcing means extending from sill 180 along lines parallel to one edge to form the car side floor portions secured to said center floor portion.

- flanges, journal boxes bolted to said vertical flanges and a center floor portion comprising a plate having flanges secured to the outer surfaces of said sill flanges, said plate flanges being slotted to receive said journal box bolts.
5. 11. In a mine car, sills having vertical flanges, journal boxes bolted to said sill flanges, axles mounted in said journal boxes and passing through said sill flanges, a center floor portion comprising a plate having flanges secured to the outer surfaces of said sill flanges, said plate flanges being slotted to receive the journal box bolts and axle housings connecting said sills and having flanges secured to said center floor portion.
10. 12. In a mine car, sills having vertical flanges and a center floor portion comprising a plate having flanges secured to said sill flanges.
15. 13. In a mine car, sills having vertical flanges, a center floor portion comprising a plate having flanges secured to the vertical flanges of said sills and journal boxes secured to said sill flanges, said plate flanges being slotted to receive the journal box securing means.
20. 14. In a mine car, sills having vertical flanges, a center floor portion secured to said sill flanges, side floor portions secured to said sills and bracing means for said side floor portions secured to the upper surface of said center floor portions.
25. 15. In a mine car, sills having vertical flanges, a center floor portion comprising a plate having flanges secured to said sill flanges, side floor portions secured to said sills, bracing means for said side floor portions secured to the upper surface of said center floor portion and journal boxes secured to said vertical sill flanges and supporting said side floor portions, said plate flanges being slotted to receive said journal box securing means and said bracing means for said side floor portions.
30. 16. In a mine car, sills having vertical flanges, a center floor portion comprising a plate having flanges secured to said sill flanges, side floor portions secured to said sills and bracing means for said side floor portions secured to said center floor portion, said plate flanges being slotted to receive said bracing means.
35. 17. In a car, angle-shaped sills and a floor below said sills flanged upwardly outside of the sills for connection therewith.
40. 18. In a car, angle-shaped sills, a floor below and lapping the outer faces of said sills and a brace member projected through and above and connected to said floor.
45. 19. In a car, sills having vertical webs, a floor below and lapping the outer faces of said sills, a brace projected through one of said members and means connecting said brace on the upper face of the floor.
50. 20. In a car, sills having vertical webs, a floor below and lapping the outer faces of said sills, axles projected through the sills and braces secured on the upper surface of the floor and projecting thence upwardly to another part of the car.
55. 21. A mine car including side floor portions, a central floor portion supported below the side floor portions, and transverse braces extending entirely across the upper face of the central floor section and secured thereto and having their ends projected beyond the central floor portion and connected to the undersides of said side floor portions to brace the latter.
60. 22. A mine car comprising a pair of sills, a central floor portion attached to the lower edges of the sills, a plurality of braces engaging the upper face of said central floor portion and having their ends projecting upwardly and laterally from the central floor portion, and side floor portions attached to the upper edges of the sills and said upwardly and laterally extended portions of the braces.
65. 23. In a mine car, sills having vertical flanges, and a center floor portion secured to the outer faces of said sill flanges.
70. 24. In a mine car, sills having vertical flanges, a center floor portion secured to the outer faces of said sill flanges, and side floor portions attached to said sills and having wheel openings therein.
75. 25. In a mine car, a body having side portions, and a floor portion and longitudinal members having vertical flanges connecting said sides and floor portion.
80. In witness whereof I have hereunto set my hand.
